INVENTOR:

HENRY ILL.

BY

Fred C. Fraenzel,
ATTORNEY

UNITED STATES PATENT OFFICE.

HENRY ILL, OF NEWARK, NEW JERSEY.

CASTER.

SPECIFICATION forming part of Letters Patent No. 544,101, dated August 6, 1895.

Application filed April 25, 1895. Serial No. 547,153. (No model.)

To all whom it may concern:

Be it known that I, HENRY ILL, a citizen of the United States, residing at Newark, in the county of Essex and State of New Jersey, have invented certain new and useful Improvements in Casters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in casters, and has for its object to provide a cheaply-constructed caster-frame, having a double bearing-surface to prevent the breaking or the straining of the connecting top plate of the caster-frame, to which the post, which is arranged in the article of furniture and in connection with which the caster is used, is secured.

To this end my invention consists in the novel construction of caster, and also in the minor arrangements and combinations of parts, to be hereinafter fully described and finally embodied in the clauses of the claim.

The invention is illustrated in the accompanying sheet of drawings, in which—
30 Figure 1 is a side elevation of the caster comprising the novel features of my invention, and Fig. 2 is a longitudinal vertical section of the same. Fig. 3 is a perspective view of the ordinary form of caster-frame and its top plate, and Fig. 4 is a like view of a strengthening-plate to be used in connection therewith.

Similar letters of reference are employed in each of the above-described views to indicate 40 corresponding parts.

In said drawings, *a* indicates the usual form of caster-frame, provided with the perforated top plate *a'*, having the downwardly-extending ears *a²*, which are perforated, as at *a⁴*, to receive the pin *b* on which is arranged the usual form of roller or wheel *b'*. To strengthen said top plate *a'* and to prevent the breaking thereof, when the caster is used on heavy pieces of furniture, is the main object of my 45 invention, and to successfully obtain this result I have arranged upon the upper surface of said plate *a'* a separately-constructed strengthening-plate *c*, having its free ends *c'*

and *c²* bent at right angles, or approximately so, and its extreme free ends *c³* and *c⁴* turned 55 beneath the under surface of said top plate *a'*, as clearly shown in Fig. 2, and then clamped fast in a press or by means of any other suitable tool. Said plate *c* is also provided with a perforation *c⁵*, which is directly over the 60 central hole or opening *a³* in the top plate *a'* of the caster-frame, and through which the end of the usual form of post *d* can be passed and riveted or otherwise secured on the under side of said top plate *a'*, as will be seen 65 from Fig. 2.

Thus it will be seen that by my arrangement of the strengthening-plate *c* on the top plate *a'* of the caster-frame I have devised a double bearing-surface for casters, which is of especial benefit in connection with cast-iron 70 caster-frames, which are subject to great strain in moving heavy furniture, and the danger of cracking the top plate of the 75 caster-frame and also that of breaking the frame is successfully overcome.

Having thus described my invention, what I claim is—

1. As an improved article of manufacture, a 80 caster, comprising therein, a frame *a* having a top-plate *a'*, and the downwardly extending ears *a²*, and a separately constructed strengthening plate *c*, having its free ends bent down at right angles, or approximately so, and turned beneath the under surface of 85 said top-plate and between said arms, substantially as and for the purposes set forth.

2. As an improved article of manufacture, a 90 caster, comprising therein, a frame *a* having a top-plate *a'*, downwardly extending ears *a²* and a hole or opening *a³*, a separately constructed strengthening plate *c* having a perforation *c⁵*, and having its free ends bent 95 down at right angles, or approximately so, and turned beneath the under surface of said top-plate, and a post in said perforations *a³* and *c⁵*, all arranged, substantially as and for the purposes set forth.

In testimony that I claim the invention set forth above I have hereunto set my hand this 100 23d day of April, 1895.

HENRY ILL.
